UNITED STATES PATENT OFFICE

115,186

DESIGN FOR A COMBINED COMB AND CURLER

Leonard G. Arpin, New York, N. Y., and Andrew J. Bedwell, Fort Lauderdale, Fla.

Application November 1, 1938, Serial No. 80,808

Term of patent 14 years

To all whom it may concern:

Be it known that we, Leonard G. Arpin and Andrew J. Bedwell, citizens of the United States and residents respectively of the city of New York, in the county of Queens and State of New York, and of the city of Fort Lauderdale, in the county of Broward and State of Florida, have invented a new, original, and ornamental Design for a Combined Comb and Curler, of which the following is a specification, reference being had to the accompanying drawing, forming a part thereof.

In the drawing:

Figure 1 is a side elevational view of a combined comb and curler showing our new design, with the movable comb element in closed position;

Figure 2 is a similar view thereof, with the movable comb element in raised position; and

Figure 3 is a cross-sectional view of the stationary comb at a point close to the root of the back of the comb as viewed in the opposite direction from the handle.

The other side of the comb is substantially like the side shown in full lines. The dominant features of the design reside in the portions shown in full lines.

We claim:

The ornamental design for a combined comb and curler, as shown and described.

LEONARD G. ARPIN.
ANDREW J. BEDWELL.
